UNITED STATES PATENT OFFICE

2,447,963

LOOSE-LEAF BINDER

Samuel Segal, New York, N. Y., assignor to Wilson-Jones Company, Chicago, Ill., a corporation of Massachusetts

Application February 21, 1944, Serial No. 523,244

3 Claims. (Cl. 129—24)

1

This invention relates to loose leaf binders of the type commonly called ring binders and it refers particularly to an improved means for providing a wire rib metal with three rings.

It is an object of this invention to provide a three ring wire rib metal with means for opening and closing the rings simultaneously. It is a further object of this invention to provide a third ring in a wire rib metal without welding. Other objects of this invention will become apparent upon reading the following description, taken in conjunction with the accompanying drawings, in which:

Figure 1 is a fragmentary top elevation of one embodiment of the invention;

Figure 2 is a cross sectional view taken along the line II—II of Figure 1;

Figure 3 is a bottom elevation of the sheet retaining mechanism illustrated in Figure 1;

Figure 4 is a cross sectional view taken along the line IV—IV of Figure 3 showing the sheet retaining mechanism secured to a binder back; and

Figure 5 is a cross sectional view similar to Figure 4, taken along the line V—V of Figure 3.

In the drawings the reference numeral 2 indicates a binder back, to which a pair of cover members 3 is secured in any conventional manner. A cover plate 4 is secured to the binder back 2 by means of a plurality of rivets or eyelets 5. If desired, the cover plate and the back member may be counter-sunk, as indicated at 6 and 7 respectively, so that the rivets will not project beyond the top surface of the cover plate or the bottom surface of the binder back. The cover plate 4 is provided with down-turned longitudinal edges 8 and is provided with a pair of transversely aligned apertures 9 for each sheet retaining ring. The apertures 9 are illustrated so as to show a solid bottom edge for the cover plate, but it will be understood that the apertures may be notched from the outer edge.

In the embodiment illustrated in Figures 1 to 5 inclusive, a pair of duplicate rockable frames 10 is diagonally positioned in the cover plate 4. The frames 10 each have both ends terminating in ring sections 11 at the center of the cover plate engage each other to form a sheet retaining ring. Each frame 10 is bent inwardly, as indicated at 12 and 13, to provide contact necks 14 and 15.

Another pair of duplicate rockable frames 16 is diagonally positioned in the cover plate 4 opposite the frames 10. The frames 16 each have one end terminating in a ring section 11 and the other end terminating in a stub section 17. The

2

frames 16 are each bent inwardly as indicated at 18, to provide a contact neck 19 adjacent the ring section 11.

The contact neck 14 is provided with a tongue 20 which engages a groove 21 in the contact neck 19 so as to provide a rocking connection between oppositely disposed companion rockable frames 10 and 16 adjacent one end thereof.

The stub section 17 of the frame 16 is bent at right angles and its end is bifurcated, as indicated at 22, so as to straddle the contact neck 15 of the oppositely disposed companion rockable frame 10. The contact neck 15 is grooved, as indicated at 23, and a rod 24 is positioned in the groove 23 to provide a rocking connection between the contact necks 15 of the diagonally positioned frames 10. The stub section 17 straddles the rod 24 as well as the contact neck 15.

From the foregoing it will be seen that the mating ring sections adjacent each end of the cover plate are provided with conventional rocking connections and that force applied to any of these rings is transmitted through the rocking connection and the straddling engagement of the stub sections with contact necks of other frames to provide simultaneous opening and closing of all three pairs of mating ring sections.

Although I have described a preferred embodiment of my invention in detail, it will be understood that the description thereof is illustrative, rather than restrictive, as many details may be modified or changed without departing from the spirit or scope of my invention. Accordingly, I do not desire to be restricted to the exact details of construction described, except as limited by the appended claims.

I claim:

1. In a loose leaf binder, a cover plate, a pair of duplicate rockable frames positioned diagonally in said cover plate, a rod extending longitudinally of said cover plate engaging the adjacent edges of said rockable frames, and a second pair of duplicate frames positioned in said cover plate, each frame of said second pair having one end straddling the oppositely disposed frame and said rod.

2. In a loose leaf binder, a cover plate, a three ring mechanism in said cover plate comprising two companion rockable frames oppositely disposed on one side of the transverse center of said cover plate and two other companion rockable frames oppositely disposed on the other side of said center, the center ring being formed by mating ring sections provided on the ends of two diagonally disposed frames, said diagonally disposed

frames each having a groove in one edge, a rod positioned in said groove, said other two diagonally disposed frames each having a stub section provided with a bifurcated end, said bifurcated ends straddling said oppositely disposed frames and said rod.

3. In a loose leaf binder, a cover plate, a pair of duplicate frames diagonally disposed in said cover plate, said frames each having a contact neck adjacent the center of said cover plate, a rod engaging both of said contact necks, and a second pair of duplicate frames each disposed opposite one of said first mentioned frames, said last mentioned frames each having a stub section engaging said rod and the contact neck of 15 the oppositely disposed frame.

SAMUEL SEGAL.
